CLAIM

We claim the ornamental design for a footwear care machine, as shown and described.

DESCRIPTION

FIG. 1 is a front perspective view of a footwear care machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view showing inside the claimed design without having shelves; and,

FIG. 10 is a perspective view showing a state in which doors thereof are closed.

The broken lines represent portions of the footwear care machine that form no part of the claimed design.

1 Claim, 10 Drawing Sheets
